UNITED STATES PATENT OFFICE.

CHARLES E. REED, OF CHICAGO, ILLINOIS, ASSIGNOR TO CHARLES E. REED & COMPANY,
OF CHICAGO, ILLINOIS.

PATTERN-GRADING MACHINE.

1,079,022.

Specification of Letters Patent.

Patented Nov. 18, 1913.

Application filed October 25, 1913. Serial No. 727,671.

To all whom it may concern:

Be it known that I, CHARLES E. REED, a citizen of the United States, residing at Chicago, in the county of Cook and State of Illinois, have invented a new and useful Improvement in Pattern-Grading Machines, of which the following is a specification.

My invention relates more especially to the type of pattern-grading machines employing an adjustable pantographic frame and model-tracing and pattern-producing elements carried thereby.

My primary objects, generally stated, are to provide, in a machine of the pantographic type and employing a traveling cutter-head, for the changing of the position of said head, as desired, relative to the model-tracer to permit additions forming laps, folds, or cloth-seams, to be produced, from a net model, on the patterns made therefrom, or produce from a model having an addition or additions patterns having no additions, and to produce patterns of the characters above stated wherein the additions or subtractions on the patterns relative to the models will be of uniform width regardless of the number of different sizes of patterns made from the model and whether the patterns to be made are larger or smaller than the model, all without disturbing the centers or size-settings of the pantographic mechanism in making the adjustments for such additions or subtractions; to provide improved means for use in any type of pantographic pattern-producing machine, for producing additions and subtractions relative to the models, on patterns without disturbing the pantographic centers and size-settings; to provide, generally, in pattern-producing machines of the pantographic type, for the production from one model of patterns for different widths of shoes, with the correct graduations for length and width necessary to produce the correct grade for either width, regardless of the patterns being larger or smaller than the model; and furthermore, if desired, permit shoe-patterns of all sizes and widths to be produced from a single model.

Referring to the accompanying drawings— Figure 1 is a plan view of a machine of the pantographic type and employing a traveling cutter-head, equipped with my improvements, a part of the machine being broken away. Fig. 2 is a section taken at the line 2 on Fig. 1 and viewed in the direction of the

arrow. Fig. 3 is a plan view of a portion of the structure illustrated in Fig. 1. Fig. 4 is a plan view of the movable pantographic frame and parts carried thereby, certain of which are illustrated in section and others thereof broken away, the section being taken at the line 4 on Fig. 2 and viewed in the direction of the arrow. Figs. 5 and 6 are enlarged sections taken at the lines 5 and 6, respectively, on Fig. 4 and viewed in the directions of the arrows. Figs. 7 and 8 are enlarged sections taken at the lines 7 and 8, respectively, on Fig. 4 and viewed in the directions of the arrows. Fig. 9 is a broken enlarged plan view of the adjusting device shown in Fig. 5. Fig. 10 is a similar view of the adjusting device of Fig. 8. Fig. 11 is a view of two superposed blucher quarter patterns of the same size and width, showing the lowermost one provided with an addition, forming a lap, produced by my improved machine. Fig. 12 is a plan view of a plurality of patterns produced from a machine embodying my improvements and from which the "quarters" for "Blucher" shoes of graduated widths may be made, the patterns being superposed to illustrate the variations in the patterns for the different widths, the graded additions on the rear edges thereof being slightly exaggerated. Fig. 13 is a broken view in vertical sectional elevation through the stationary and one of the movable frames of the machine showing the pattern-cutting mechanism in elevation; and Fig. 14, a view in front elevation of the machine shown at the right-hand side of Fig. 1.

As the machine in connection with which I have chosen to illustrate my invention is, as to its general features of construction, of a type commonly used in the manufacture of shoe patterns, it is unnecessary that I describe all the details of the machine, a general description only as follows being necessary.

The stationary frame of the machine is represented at 9 and is equipped with roller-engaging guide-surfaces 10 for the rollers 11 of the frame 12 freely movable on the rollers back and forth on the frame 9. The frame 12 is provided with roller-engaging guide-members 13 for rollers 14 and 15 on a pair of frames 16 and 17, which are freely movable on the frame 12 at right angles to the movement of the latter, the frame 16 being

provided with roller-engaging guide-surfaces 18 for rollers 19 on a frame 20, forming the cutter-head, and surmounting the frame 16 and movable back and forth on the latter. 3 The frame 17, as is usual in practice, carries the model-tracing element represented at 100 which in the operation of the machine is manually moved by the operator against the periphery of a pattern-model, as for example, the model shown at 101 and which is supported on a table 21 on the frame 9. The frame 20, as commonly constructed, is of yoke-shape affording upper and lower arms 102 and 103 respectively, the arm 102 being 15 hollow and containing in its front end the vertically reciprocable male element 104 of a punch device forming the pattern-cutter and being operated by any suitable means (not shown), but which are preferably contained within the arm 102; and the arm 103 carrying the female member 105 of the punch device.

Pivoted on the frames 16 and 17, as indicated at 21 and 22, are grading levers 23 and 24, respectively, in the form of quadrants, the lever 23 at its right-hand end (Fig. 2) being pivoted, as indicated at 25, to a coupling-member 26 pivoted, as indicated at 27, to a carriage 28 guidedly carried by rollers 29 on a cross-bar 30 supported on the stationary frame 9, and the rear end of the lever 24 being pivotally connected at 31 with the forward end of a connecting link 32 pivoted at its rear end, as indicated at 33, to a block 34 slidably confined to move back and forth on a guide 35 on the frame 12.

Mounted on the levers 23 and 24 are clamping-heads 36 and 37, respectively, these heads being adapted to be adjusted to any desired position along the levers and clamped in adjusted positions thereon, as by clamping means 38, in accordance with common practice. The frame 16 is connected with the clamping-head 37 through the medium of a radius bar 39 pivotally connected at one end, as indicated at 40, to the frame 16 and at its opposite end, as indicated at 41, to the head 37, this bar, in accordance with my invention, being formed of sections 42 and 43 adjustably connected together, as hereinafter described. The frame 20 is connected with the clamping-head 36 through the medium of a radius bar 44 which is pivotally connected with the frame 20, as indicated at 45, and with the head 36, as indicated at 46, this bar, in accordance with my invention, being formed of relatively-adjustable sections 47 and 48 adapted to be held in adjusted position by 60 the means hereinafter described.

As is well understood in the art, the adjustment of the various movable frames referred to and their connecting parts for cutting patterns of different sizes from a single model, is effected by adjusting the clamping-

heads 36 and 37 on the respective levers 23 and 24, and adjustments for producing irregular grades are produced by adjusting the levers 23 and 24 relative to the connectors 26 and 32, respectively, to vary the angular relations at which these parts extend relative to each other, clamping means, as for example, those illustrated at 49 being employed for rigidly holding the said levers and connectors in adjusted position. 75

In the construction illustrated, the bars 39 and 44 are adapted to be lengthened and shortened, as desired, and held in such adjusted position for the purpose of adjusting the frames 16 and 17, and 16 and 20, relative to each other, for the purpose hereinafter explained, and to this end, I prefer to construct these bars, and provide clamping mechanism therefor, as illustrated in the drawings and of which the following is a 85 description: The section 42 of the bar 39 terminates in a dovetail tongue 50 which slidingly interfits with the undercut walls 51 of a longitudinally extending groove 52, of dovetail form in cross-section, provided in the top surface of the bar section 43. A bolt 53 headed, as indicated at 54, to enter a countersunk opening 55 in the undersurface of the tongue 50, extends upwardly through the tongue 50 and through a lever 56, wherein it has journal fit, pivotally connected at one end, as indicated at 57 to a link 58, pivotally connected as indicated at 59 to the bar-section 43. The upper threaded end of the bolt 53 carries a nut 60 which operates, 90 when screwed down, upon the bolt 53, to draw the tongue 50 into tight frictional engagement with the undercut walls 51 of the groove 52 and thus frictionally clamp together the sections 42 and 43 of the bar 39, 105 it being understood that these bar-sections may be adjusted lengthwise of each other by swinging the lever 56 on its pivot 57, and, if desired, a scale 61 may be provided on the bar-section 42 for coöperation with 110 a pointer 62 on the bar-section 43, or, if desired, the positions of the scale 61 and pointer 62 may be reversed, or a scale (not shown) may be provided on an arc-shaped bar 63 for coöperation with the swinging 115 end of the lever 56. The sections 47 and 48 of the bar 44 are connected together, as follows: The bar-section 47 is formed (at its forward end) with a dove-tail tongue 64, interfitting with a dove-tail groove 65 in the bar-section 48. A bolt 66 has screw engagement at its lower end, as indicated at 67, with the tongue-end of the bar-section 47 and passes up through a lever 68, wherein it has journal fit, pivoted, as indicated at 69, to a link 70, pivoted to the bar-section 47, as indicated at 71, the upper end of the bolt 66 being headed, as indicated at 72, and provided with a finger grip 73, whereby the bolt 66 may be screwed up or down in 120 125 130

the section 47. The underside of the tongue 64 is counterbored, as indicated at 74, and contains therein a block 75 resting on the bottom of the groove 65, the bolt 66 co-operating with said block and serving, when said bolt is screwed down, to cause the tongue 64 to be forced upwardly into clamping engagement with the walls of the groove 65 for releasably clamping the sections 47 and 48 together in adjusted positions. It will thus be understood that the bars 39 and 44 are thus rendered in effect expandible and contractible for adjusting the frames 16 and 17 and the frames 20 and 16, respectively, relative to each other.

It will further be understood that by adjusting the sections 42 and 43, of the bar 39, the frame 16, with all the operative parts carried thereby, may be shifted to the right or to the left in Fig. 9, relative to the frame 17, as desired, for producing on the pattern, at either or both opposite sides thereof, a lap or laps, as the case may be, of the desired width, it being understood that to produce laps on both of opposed sides of the pattern, the bar 39 must be adjusted to throw the frame 16 to one side of its normal position for producing a lap on one side of the pattern, and when said lap has been produced, must throw the frame 16 in the opposite direction beyond its normal position to produce a lap on the opposite edge, Fig. 11 of the drawings showing two superposed patterns for the quarter of a Blucher shoe, the uppermost pattern represented at 76 being unprovided with such an addition, and used where the pattern is to be used in cutting the quarter from leather; whereas the lowermost pattern 77, which is used in cutting the quarter from fabric wherein provision for a greater seam must be made, is provided with such an addition represented at 78, produced by shifting the frame 16 and consequently the pattern-cutter to the left in Fig. 4 and as represented by dotted lines of the bar-section 42 at the left in Fig. 9, before cutting the left-hand edge of the pattern. By adjusting the bar-sections 47 and 48 relative to each other, as hereinbefore stated, the frame 20 may be adjusted back and forth relative to the frame 16 and thus a lap or laps may be produced on the patterns at the opposed sides thereof other than those the formation of the laps on which are controlled by adjusting the sections of the bar 39, and where the production of a lap of such shape is required as to involve both length and width adjustments of the frames, this may be effected by a combination of adjustments of the bars 39 and 44.

In Fig. 12 I have illustrated five superposed patterns made from the machine for the quarters of Blucher shoes the middle one of which, for example, is of model size,

graduated successively to different widths but all for the same length of shoe. For each width the pattern must be made slightly larger or smaller throughout certain of its portions where it is to be respectively larger or smaller than the model size, and not only must the edges of the patterns at which the additions or subtractions, as the case may be, occur at certain portions thereof, taper and merge into the edges of the patterns, as represented, in exaggerated condition, at 79, but certain of the additions or subtractions, as the case may be, required to be made, occur along curved surfaces of the patterns, as represented at 80, 75 and are of different widths at their opposite ends as indicated at 81 and 82. It will be understood that the additions or subtractions, relative to the model, and represented at 83 and 84, along the straight or comparatively straight sides of the patterns are made by shifting the cutter-head frame relative to the model-tracer by shifting the frame 20 relative to the frame 16 in the appropriate directions, as hereinbefore set forth, but in a single direction for cutting each side, whereas the production of additions or subtractions relative to the model along the curved lines, as for example, the additions and subtractions 80 require a combination of adjustments of the cutter-equipped frame relative to the tracer elements as by adjusting the sections of both bars 39 and 44, to shift the cutter-head into the proper position relative to the tracer, thus adjusting the cutter-head causing the edges of the portions 81 and 82 to merge into each other, as distinguished from forming an abrupt offset where the portions 81 stop and the portions 82 begin.

By the use of the adjustments between the sections of the bars 39 and 44 not only may additions and subtractions, relative to the model, be made on any portion of a pattern produced otherwise the same as said model, but by the same adjustments the same additions or subtractions, non-graded in width, may be made on all sizes of patterns made from said model, without disturbing the centers or size-settings of the machine. Furthermore, it will be readily understood that by reason of the dual adjustments of the sections of the bars 39 and 44, which permit of additions or subtractions being made at all sides of the pattern, patterns of different widths, with all of the required dimensions, including those of the ankle and instep and whether larger or smaller than the model may be made from the same net model, and, if desired, all sizes and widths of patterns may be made from the same net model.

While I have shown a machine in which the connecting means between the grading levers 23 and 24 and the frames 20 and 16,

130

respectively, are rendered expandible and contractible, and securable in adjusted position by certain specific mechanism, I do not wish to be understood as intending to limit my invention to the employment of such specific mechanism, as any other mechanism suitable for this purpose may be employed; and furthermore, I do not wish to be understood as intending to limit my invention to the use of the specific clamping means employed for both the bars 39 and 44, as such mechanism may be used in a machine in which adjustment of but one connecting member is provided for. Furthermore it will be readily understood by those skilled in the art that certain features of my invention are useful in machines employing a pattern-marking element wherein the pattern is merely marked on the blank material, as well as in machines employing means for cutting out the patterns from the blanks. Accordingly certain of the following claims refer to a "pattern-forming element" and by such designation I wish to be understood as intending to claim either a pattern-marking or pattern-cutting element.

What I claim as new and desire to secure by Letters Patent is—

1. In a machine of the character set forth, the combination of traveling model-tracing and pattern-cutting elements, pantographic mechanism connecting said elements together, said pattern-cutting element being adjustable relative to said model-tracing element without disturbing the centers or size-settings of said pantographic mechanism, and means for securing said elements together in relatively adjusted positions, for the purpose set forth.

2. In a machine of the character set forth, the combination of traveling model-tracing and pattern-cutting elements, pantographic mechanism connecting said elements together and adjustable for proportioning the travel of said cutting element relative to said tracing element, said pattern-cutting element being adjustable relative to said model-tracing element without disturbing the centers or size-settings of said pantographic mechanism, and means for securing said elements together in relatively adjusted positions, for the purpose set forth.

3. In a machine of the character set forth, the combination of model-tracing and pattern-forming elements, pantographic mechanism connecting said elements together, said pattern-forming element being adjustable in a path toward and away from said model-tracing element and also in a direction at an angle to said path and without disturbing the centers or size-settings of said pantographic mechanism, and means for securing said elements together in relatively adjusted positions, for the purpose set forth.

4. In a machine of the character set forth, the combination of model-tracing and pattern-forming elements, pantographic mechanism connecting said elements together and adjustable for proportioning the travel of said pattern-forming element relative to said tracing element, said pattern-forming element being adjustable in a path toward and away from said model-tracing element and also in a direction at an angle to said path and without disturbing the centers or size-settings of said pantographic mechanism, and means for securing said elements together in relatively adjusted positions, for the purpose set forth.

5. In a machine of the character set forth, the combination with model-tracing and pattern-forming elements, of pantographic mechanism connecting said elements together and including a bar pivoted to one of said elements and connecting said elements together, said bar being constructed and arranged to permit said pattern-forming element to be adjusted relative to said model-tracing element without changing the point on said element at which said bar is pivoted and without disturbing the centers or size-settings of the machine, and means for securing said elements together in relatively adjusted positions.

6. In a machine of the character set forth, the combination of model-tracing and pattern-forming elements and pantographic mechanism connecting said elements together and including a frame and bars, one of which latter is pivoted on said frame and is operatively connected with one of said elements and the other of which bars is pivotally connected with the other of said elements and connected with said frame, said mechanism being adjustable at its bar-positions for adjusting said pattern-forming element relative to said model-tracing element without disturbing the centers or size-settings of said pantographic mechanism, and means for holding said bar-positions together in adjusted positions, for the purpose set forth.

7. In a machine of the character set forth, the combination of model-tracing and pattern-forming elements and pantographic mechanism connecting said elements together and including a frame and bars, one of which latter is pivoted on said frame and is operatively connected with one of said elements and the other of which bars is pivotally connected with the other of said elements and connected with said frame, said mechanism being adjustable for proportioning the travel of said pattern-forming element relative to said model-tracing element, and adjustable at its bar portions for adjusting said pattern-forming element relative to said model-tracing element without disturbing the centers or size-settings of

said pantographic mechanism, and means for holding said bar-portions together in adjusted positions, for the purpose set forth.

5 8. In a machine of the character set forth, the combination of model-tracing and pattern-forming elements and pantographic mechanism connecting said elements together and including a frame, grading levers pivoted on said frame and one of said elements, and bars one of which is pivoted on said frame and is operatively connected with the one of said levers on one of said elements and the other of which bars is pivotally connected with the other of said elements and connected with the lever on said frame, said connections of the bars with said levers being adjustable to vary said points of connection relative to the pivots 10 of said levers and said mechanism being also adjustable at its bar-portions for adjusting said pattern-forming element relative to said model-tracing element without disturbing the centers or size-settings of said 15 pantographic mechanism, and means for securing said elements together in relatively adjusted positions, for the purpose set forth.

9. In a machine of the character set forth, the combination of model-tracing and pattern-forming elements and pantographic mechanism connecting said elements together and including a frame and bars formed of sections adjustably connected together and adapted to be lengthened and shortened, one of said bars being pivoted on said frame and pivotally connected with one of said elements and the other of said bars being pivotally connected with the other of said elements and connected with said 20 frame, for the purpose set forth.

10. In a machine of the character set forth, the combination of model-tracing and pattern-forming elements and pantographic mechanism connecting said elements together and including a frame, grading levers pivoted on said frame and one of said elements, and bars each formed of sections adjustably connected together and adapted to be lengthened and shortened, one of said 25 bars being pivoted on said frame and operatively connected with the one of said levers on one of said elements and the other of said bars being pivotally connected with the other of said elements and connected 30 with the lever on said frame, said connections of the bars with said levers being adjustable to vary said points of connection relative to the pivots of said levers, for the purpose set forth.

60 11. In a machine of the character set forth, the combination with model-tracing and pattern-forming elements and a movable frame, of means, forming with said frame pantographic mechanism and con-

necting said elements with said frame, said means being constructed and arranged to permit said frame and pattern-forming element to be adjusted relative to said model-tracing element and said pattern-forming element to be adjusted relative to said frame and model-tracing element without disturbing the centers or size-settings of said pantographic mechanism, and means for securing said elements together in relatively adjusted positions, for the purpose set forth.

12. In a machine of the character described, the combination of separate frames carrying the pattern-forming and model-tracing elements and pantographic mechanism including a third separate frame which is interposed therebetween and connectors separately connecting together the frames carrying said elements with said third frame, said connectors being independently 80 adjustable without disturbing the centers or size-settings of said pantographic mechanism, and means for holding said elements and said third frame in relatively adjusted 85 positions, for the purpose set forth. 90

13. In a machine of the character described, the combination of separate frames carrying the pattern-forming and model-tracing elements and pantographic mechanism including a third separate frame which is interposed between said first-named frames, and connectors separately connecting together the frames carrying said elements with said third frame, said connectors being provided with pluralities of 95 adjustments certain of which serve to position said pattern-forming element relative to said model-tracing element for proportioning the travel of the former relative to the latter and others of which serve to permit said pattern-forming elements to be shifted bodily relative to said model-tracing element without disturbing the centers or size-settings of said pantographic mechanism, and means for securing together said 100 elements and said third frame in adjusted 105 positions, for the purpose set forth. 110

14. In a machine of the character described, the combination of a reciprocable frame, a pair of frames mounted on said 115 first-named frame and reciprocable thereon transversely of the movement of the latter, a model-tracer on one of said pair of frames, a third frame mounted on the other of said pair of frames, a pattern-forming device on 120 said last-named frame, a member guidedly confined on said first-named frame and reciprocable in the same direction as the frame equipped with said pattern-forming device, a second member guidedly confined 125 to reciprocate in the direction of movement of said pair of frames, grading levers pivoted on said pair of frames and connected

- 6
- eccentrically of their pivots with said members, respectively, heads adjustably connected with said levers, and adjustable connectors adjustably connecting the head on 5 the one of said levers which is pivoted to said tracer-equipped frame with the other of said pair of frames and the other head with the frame equipped with said pattern-forming device, for the purpose set forth.
- 10 15. In a machine of the character described, the combination of a reciprocable frame, a pair of frames mounted on said first-named frame and reciprocable thereon transversely of the movement of the latter, 15 a model-tracer on one of said pair of frames, a third frame mounted on the other of said pair of frames, a pattern-forming device on said last-named frame, a member guidedly confined on said first-named frame, and re- 20 ciprocable in the same direction as the frame equipped with said pattern-forming device, a second member guidedly confined to reciprocate in the direction of movement of said pair of frames, grading levers piv- 25 oted on said pair of frames and connected eccentrically of their pivots with said members, respectively, heads adjustably connected with said levers, and bars each formed of longitudinally adjustable sections for 30 lengthening and shortening said bars, adjustably connecting the head on the one of said levers which is pivoted to said tracer- 35 equipped frame with the other of said pair of frames and the other of said heads with the frame equipped with said pattern-forming device, for the purpose set forth.
16. The combination with model-tracing and pattern-forming elements, of a bar connecting said elements together and formed 40 of sections adjustable relative to each other, a lever fulcrumed on one of said sections and connected with the other of said sections, and means for securing said lever in 45 adjusted position.
- 45 17. The combination with model-tracing and pattern-forming elements, of a bar connecting said elements together and formed of longitudinally adjustable sections, one of 50 which is longitudinally grooved and the other of which extends into said groove, a lever fulcrumed on one of said sections and engaging with the other of said sections, and means for securing said lever in 55 adjusted position.
- 55 18. In a machine of the character set forth, the combination with model-tracing and pattern-forming elements, of a bar pivoted to one of said elements and connecting said elements together, said bar being 60 formed of longitudinally adjustable sections, a lever fulcrumed on one of said sections and connected with the other of said sections, and means for securing said lever in 65 adjusted position.
19. In a machine of the character set forth, the combination with model-tracing and pattern-forming elements, of a bar pivoted to one of said elements and connecting said elements together, said bar being 70 formed of longitudinally adjustable sections, one of which is longitudinally grooved and the other of which extends into said groove, a lever fulcrumed on one of said sections and engaging with the other of said sections, and means for securing said lever 75 in adjusted position.
20. The combination of a main stationary frame, guide means thereon extending in one direction, a second frame mounted on said main frame and movably confined on 80 said guide means, guide means on said second frame extending at right-angles to said first-named guide means, a third frame movable on said second frame, a model-tracing element and a pattern-forming element 85 movable on said second frame, one of said elements being carried by said third frame and adjustable thereon at right-angles to its movement on said second frame, adjustable means connecting said third frame with 90 said elements for adjusting said elements toward and away from said third frame, without disturbing the centers or size-set- 95 tings of the machine, and means for securing said elements together in relatively adjusted positions.
21. The combination of a main stationary frame, guide means thereon extending in one direction, a second frame mounted on said main frame and guidedly confined on 100 said guide means, guide means on said sec- 105 ond frame extending at right-angles to said first-named guide means, a third frame movable on said second frame, a model- tracing element and a pattern-forming ele- 110 ment movable on said second frame, one of said elements being carried by said third frame and adjustable thereon at right angles to its movement on said second frame, bars formed of adjustable sections connect- 115 ing said third frame with said elements, the sections of said bars being adjustable relative to each other without disturbing the centers or size-settings of the machine, and means for securing together the sections of said bars in adjusted positions.
22. The combination of a main stationary frame, guide means thereon extending in one direction, a second frame mounted on said main frame and movably confined on 120 said guide means, guide means on said sec- 125 ond frame extending at right-angles to said first-named guide means, a third frame movable on said second frame, a model-tracing element and a pattern-forming element movable on said second frame, one of said elements being carried by said third frame and adjustable thereon at right angles to

its movement on said second frame, grading levers connected with said third frame and with the other of said elements, adjustable means connecting a grading lever on said

5 third frame with the one of said elements which is movable on the latter and the other of said grading levers with the other of

said elements, and means for securing said elements together in adjusted positions relative to said frame.

CHARLES E. REED.

In presence of—

W. B. DAVIES,
E. D. STEELE.
